UNITED STATES PATENT OFFICE.

GEORGE TEWKSBURY JOHNSON, JOHN STEWART MCPHERSON, AND HARRY HAMILTON WOLFE, OF COLUMBUS, OHIO, ASSIGNORS TO THE BUCKEYE STEEL CASTINGS COMPANY, OF COLUMBUS, OHIO.

CAR-COUPLING DEVICE.

Application filed November 23, 1923. Serial No. 676,573.

This invention relates to coupling devices and has special reference to devices for connecting an automatic M. C. B. coupler head with a hook-type coupler, the object of the invention being to provide a connection which will be permanently connected with the M. C. B. coupler head so that loss and theft will be guarded against, to utilize parts which are now standard equipment in the hook coupler and thereby keep down the cost of installation, and to provide a connection which will readily accommodate itself to unequal loading of the cars and will not interfere in any way with the usual operation of the automatic M. C. B. coupler. The invention is illustrated in the annexed drawings and will be herein-after fully set forth.

In the drawings, Figure 1 is a plan view of the improved device;

Figure 2 is a side view of the same under pulling strain;

Figures 3 and 4 are side views showing the cars in buffering position and also illustrating variations in position due to unequal loading of the cars;

Figure 5 is a detail.

The M. C. B. coupler head 1 is, in the present instance provided on the outer side of the guard arm with an eye 2 preferably slightly elongated and diverging forwardly from the longitudinal axis of the head. On the opposite side of the head and alined transversely with the center of the eye is a headed stud 3, the head of which is flattened on its opposite side edges whereby it is given a substantially elliptical form with its major axis inclined downwardly and rearwardly, as shown in Fig. 5. The device includes a triangular link 4 which is engaged over the hook coupler 5 and which is engaged and carried by the clevises 6 which are part of the usual equipment of the hook-type coupler. Clevises 7 and pins 8 connecting them to the clevises 6 are also employed and these parts are also usual equipment on the hook-type coupler. In assembling the parts, one clevis 7 is engaged over the stud 3 and the other clevis 7 is engaged through the eye 2; the ends of the respective clevises 6 are then fitted in the open ends of the clevises 7, as shown in Fig. 2, and the pins 8 inserted through the ends of the clevises. Small locking pins 9 are in-

serted through the lower ends of the pins 8 and upset, whereupon the clevises will be permanently attached to the coupler head, at least to such a degree that they can be removed only with the use of efficient tools and after laborious effort.

When two automatic couplers are brought together so that the use of the transition device herein described is unnecessary, the device is suspended below the coupler head from the eye 2 and stud 3 so that it will be out of the way and will not interfere at all with the operation of the coupler.

When a car with the hook-type of coupling is coupled to a car fitted with an automatic coupler carrying this improved device and the cars are separated under pulling strain, the clevises and the triangular link will be substantially in alinement, but when the pulling strain reduces and the cars come together in buffering position, the device folds downward and swings more or less under the coupler head accordingly as one or the other car is carrying the heavier load, as will be understood on reference to Figures 3 and 4.

Instead of providing a stud 3 at one side of the head, eyes 2 may be provided at both sides of the head.

By referring to Fig. 5, it will be readily understood that if the link be placed in an inclined position so that its major axis will coincide with or lie parallel to the major axis of the stud 3, it may be easily shifted into engagement with the stud behind the head thereof and the head will prevent its disengagement or release under all ordinary conditions as, in order to be released, the link must be rocked transversely while its length extends in the same direction as the length of the stud. The obliquely disposed eye 2 and the shank of the stud permit a limited play of the links to accommodate the movement of the cars toward or from each other as the pulling strain increases or decreases and will accommodate the relative angular movement of the cars in rounding curves without permitting detachment of the links. It will also be noted that the links are mounted on the head without requiring any additional openings to be formed through the head to weaken the same or the employment of any extraneous retaining devices.

Having fully described our invention what we claim as new and desire to secure by Letters Patent, is:—

In a coupling device of the class described, the combination of an automatic coupler head having a laterally projecting eye on one side and a lateral stud on the opposite side, said stud having a substantially elliptical head with the major axis of the head extending downwardly and rearwardly, a link to be engaged with a hook coupler, a series of clevises having one end

member engaged permanently with said link and another end member engaged over the stud behind the head thereof, and a series of clevises having one end member permanently engaged with the link and another end member permanently engaged in the eye.

In testimony whereof, we have signed this specification.

GEORGE TEWKSBURY JOHNSON.

JOHN STEWART McPHERSON.

HARRY HAMILTON WOLFE.
